CLAIM

The ornamental design for an earring, substantially as shown and described.

DESCRIPTION

FIG. 1 is a perspective view of an earring showing my new design;

FIG. 2 is a front elevational view of the design illustrated in FIG. 1;

FIG. 3 is a right side elevational view of the design illustrated in FIG. 1;

FIG. 4 is a left side elevational view of the design illustrated in FIG. 1;

FIG. 5 is a rear elevational view of the design illustrated in FIG. 1;

FIG. 6 is a top plan view thereof;

FIG. 7 is a bottom plan view thereof;

FIG. 8 is a front elevational view of an earring showing a modified form of my new design;

FIG. 9 is a front elevational view of an earring showing another modified form of my new design.

FIG. 10 is a left side elevational view of the design illustrated in FIG. 9.
